UNITED STATES PATENT OFFICE.

MICHAEL JOSEPH O'HARA, OF NEW ORLEANS, LOUISIANA.

ANTI-FRICTION JOURNAL-BEARING.

SPECIFICATION forming part of Letters Patent No. 391,184, dated October 16, 1888.

Application filed June 12, 1888. Serial No. 276,891. (No model.)

To all whom it may concern:

Be it known that I, MICHAEL JOSEPH O'HARA, a citizen of the United States, residing at New Orleans, in the parish of Orleans and State of Louisiana, have invented certain new and useful Improvements in a Journal for Starting a Car; and I do declare the following to be a full, clear, and exact description of the invention, such as will enable others skilled in the art to which it appertains to make and use the same.

This invention relates to improvements in lubricating journal-boxes of the class in which friction-rollers are employed; and it consists in the construction, novel arrangement, and adaptation of devices, as will be hereinafter more fully set forth, and particularly pointed out in the claim appended.

In the accompanying drawings, Figure 1 is a vertical cross-sectional view of a car-axle spindle, the same continuing through my improved axle-box and lubricator. Fig. 2 is a horizontal sectional view of the box removed from the axle-spindle. Fig. 3 is a plan view of the box. Fig. 4 is a detail view of one of the friction-rollers which I employ, and Fig. 5 is a view of one of the bearings for the said rollers removed from the box.

Referring by letter to the said drawings, A indicates an axle-spindle, which may be that of a street-car axle.

B indicates my improved axle-box, which is of a form substantially as shown, and provided in its upper side longitudinally with an oil or lubricant receptacle, A, which may be covered with a suitable plate or top to prevent rapid evaporation and exclude dust, dirt, and the like. This box B is, furthermore, provided at opposite sides with longitudinal vertical flanges, which depend from the receptacle a sufficient distance and are adapted to embrace the axle-spindle, as more fully shown in Fig. 1 of the drawings.

C indicates bearing-blocks for friction-rollers, the form of which is better shown in Fig. 5 of the drawings, and there is one of these blocks employed transversely at each end of the box beneath the lubricant-chamber. These blocks are grooved vertically at opposite ends, as shown at d, to receive tongues or projections e, formed at opposite points on the inner sides of the vertical flanges of the box B, so that the said blocks may be prevented from lateral displacement and yet allowed to adjust themselves with respect to the axle-spindle. 55

D indicates the friction-rollers, which have an upper bearing in the seats f of the blocks C, and these rollers have spindles, as shown at g, to enter the seats f of the block C. It will be observed that these rollers extend the entire length of the box beneath the lubricant-receptacle, and that the floor of the said receptacle is provided with small apertures h, so that the lubricating material may be fed upon the friction-rollers and from them discharged on the spindle of the axle. It will be observed that these rollers have a bearing upon the axle-spindles. 65

Having described my invention, what I claim is—

The combination, with the axle-box having the upper lubricant-receptacle provided with a perforated bottom and the depending flanges adapted to embrace an axle-spindle and provided with the tongues, as shown, of the bearing-blocks grooved at opposite ends to receive the tongues on the flanges of the box, and the friction-rollers arranged above the axle-spindle and having an upper bearing against the said blocks. 75

In testimony whereof I affix my signature in presence of two witnesses.

MICHAEL JOSEPH O'HARA.

Witnesses:

JACOB BURKHARDT,
LAWRENCE MURRAY.
